UNITED STATES PATENT OFFICE.

JOHN AARON PETERSON, OF KANE, PENNSYLVANIA.

STAPLE PULLER.

Application filed April 14, 1925. Serial No. 23,077.

To all whom it may concern:

Be it known that I, JOHN AARON PETERSON, a citizen of the United States of America, and a resident of Kane, county of Mc-

5 Kean, State of Pennsylvania, have invented certain new and useful Improvements in and Relating to Staple Pullers, of which the following is a specification.

This invention relates to certain improvements in staple pullers; and the nature and objects of the invention will be readily recognized and understood by those skilled in the arts involved in the light of the following explanation and detailed description 10 of the accompanying drawings illustrating what I at present consider to be the preferred embodiments or mechanical expressions of my invention from among various other forms, embodiments, combinations, 15 and constructions of which the invention is capable within the spirit and scope thereof.

More particularly the invention is directed and deals with a staple puller primarily adapted for use in erecting and repairing fences of the wire types in which the wire is secured and fastened in position by staples or similar fastening means, on and to wood or similar material posts or supports. The staples securing and fastening fence wire to the supporting posts are of necessity driven firmly onto the wire to bind the same against the posts, and the heads of such staples are generally found to be in such position against or partially 20 embedded in the posts as to make it exceedingly difficult to force the conventional staple pulling implements or tools thereunder to secure a sufficient hold to pull or draw the staples. This difficulty is en- 25 countered particularly in withdrawing staples which have been in position a considerable period of time and subjected to the action of the elements, as in withdrawing staples to repair or mend fences.

40 Therefore, one of the main objects of the present invention is to provide a staple puller which is capable of pulling or drawing staples easily and quickly from the member into which driven, irrespective of 45 the condition of a staple or the position thereof in the member.

A further object of the invention is to provide a staple puller for efficiently withdrawing or extracting staples, which puller 50 also forms and provides a hammer for driving staples and for general use where a

hammer is desired, the construction and arrangement being such that a compact, readily portable, and easily operated tool or implement is formed.

60 A further object of the invention is to provide a staple puller which also forms a hammer, and in which the hammer forming member of the device is utilized to co-operate and function with the staple pulling member to secure a hold on a staple and extract the staple from the element in which driven.

65 Another object of the invention is to provide a staple puller and driving hammer, 70 with a wire cutting member operated by and in cooperation with the hammer member and the staple pulling member of the implement or tool so formed.

75 A further object of the invention is to provide a staple puller which is adapted to also form a driving hammer, with an arrangement of operating handles to permit of the implement being readily grasped in one hand for use as a hammer, or to be grasped in and by both hands for holding and operating the members thereof in using the implement as a staple puller.

80 A further object of the invention is to provide a combined staple puller and hammer with locking mechanism for securing the members of the implement in hammer forming relation and for releasing the members to permit of their operation as 85 a staple puller.

90 Another object of the invention is to provide a combined staple puller and hammer with an arrangement for attaching thereto and supporting a container therefrom in such a position that the staple puller and 95 hammer in hammer forming relation forms a readily grasped supporting handle for the container.

100 A further object of the invention resides in the provision of a compact and efficient staple puller and hammer of simple construction which will be durable in service and capable of manufacture at low cost.

105 With the foregoing main objects, and certain other objects and results in view, which other objects and results will be readily apparent to those skilled in the art, the invention consists in certain novel features in construction and in combination and arrangement of elements, as will be more 110 fully and particularly referred to and specified hereinafter.

Referring to the accompanying drawings, in which similar reference characters refer to corresponding parts throughout.

Fig. 1 is a side elevation of a staple puller 5 of the invention in position for engaging and pulling a staple, a portion of a staple being more or less diagrammatically indicated;

Fig. 2 is a side elevation of the staple 10 puller with the members thereof locked in position cooperating to form a hammer and handle therefor, parts being broken away to show the mounting of the locking mechanism and the wire cutting blade;

Fig. 3 is an end elevation of the head of 15 the staple puller and hammer;

Fig. 4 is an end elevation of the handle of 20 the staple puller; and

Fig. 5 is a transverse section taken on 25 the line 5—5 of Fig. 2, showing the mounting and arrangement of blade to form the wire cutter.

While the embodiment of the staple puller of the invention disclosed and described 30 herewith is primarily adapted for use in the erection and repair of fences of the wire types, the invention is not limited to such use, but is adapted for use generally in extracting fasteners of the staple type 35 and as a hammer of universal application. The mechanical expression of the invention hereof is presented purely by way of example and not of limitation to illustrate the principles and features of the invention, and the use thereof in the erection and repair of fences permits of more clearly bringing forth these principles and features 40 because the problems solved and disadvantages overcome thereby are encountered in a high degree in such use.

According to the embodiment illustrated in the accompanying drawings, a staple puller of the invention includes a pair of lever or arm members 10 and 11 which are 45 pivotally connected and joined at one end to each other in substantially parallel normal relation, by a transverse pivot pin or the like 12. In the present instance the end of member 11 is formed with the longitudinal ear 14 which is received and fitted between the parallel spaced ears 15 of member 10, with pin 12 extending through these ears, as will be clear by reference to Fig. 5 in particular. In this manner the lever members 10 and 11 are pivotally joined at one end and free at the opposite ends for 50 swinging movement toward and from each other.

The free end of the member 10 is provided with a transversely disposed staple 55 engaging and fulcrum forming head 20, flattened at the inner end 21 adjacent the member 11, and extended outwardly from member 10 at the opposite end to form the pointed staple engaging end 22 which is

bent or curved inwardly toward and longitudinally of the member 10 and has the outer side thereof longitudinally curved to provide the fulcrum or bearing surface 23, as will be more fully explained and referred to 60 hereinafter. The lever member 10 is formed of a greater width for a portion of its length adjacent to and extending from head 20 toward the pivoted end of the lever, and this widened portion is formed with opposite 65 concave sides 24 to provide a hand or finger hold in the operation of the staple puller.

The arm 11 is provided at its free end with the transversely disposed hammer forming head 30 extended outwardly a distance beyond the member 11, and at its inner end 31 adjacent head 20 it is flattened to engage the flattened inner end 21 of head 20. The inner ends 21 and 31 of the opposite heads 20 and 30, respectively, are extended a slight distance beyond the arms 10 and 11, respectively, while the heads are aligned longitudinally at their inner ends so that in normal position of arms 10 and 11 70 swung toward each other these heads abut 75 and space the arms a slight distance apart, as clearly shown by Figs. 1 and 2 of the drawings. Arm 11 is formed with a handle 32 disposed longitudinally and forming a part thereof and extending outwardly and spaced therefrom throughout a portion of the length of arm 11 from the pivoted end thereof to a point intermediate head 30 and the pivoted end. This handle 32 provides for the operation of arm 11 and hammer 80 head 30 in forcing the pointed end of head 20 into engagement with a staple.

Mechanism for detachably locking the heads 20 and 30 with arms 10 and 11, into 85 position swung together, is provided, and 90 in the example hereof comprises a strip of resilient spring material forming a clip 33 pivotally mounted at one end to the outer forward side of head 30, adjacent the inner end thereof, by a pivot pin 34, and provided 95 at its free end with a stud or projection 35 on and extending from the inner side of the clip 33. The head 20 is formed with a depression 26 (see Fig. 3) and the head 30 is 100 formed with a similar depression 36 (see Fig. 2) for receiving the clip stud 35 and confining the clip 33 in the desired position, 105 as will be readily apparent. When it is desired to lock the members 10 and 11 into 110 position, the spring clip 33 is swung over 115 onto head 20 until stud 35 snaps into the depression 26, thus securely holding and locking the members and heads 20 and 30 together. To release and unlock the members 10 and 11 with their respective heads, clip 33 is sprung away from head 20 and then 120 swung back onto head 30 and there retained in position by stud 35 in depression 36.

A further feature of the invention provides for operation of the staple puller as 125

a wire cutter. A cutting blade 40 is detachably mounted by means of a screw-threaded shank 41 on the inner side edge of the lever member 10, adjacent and in proximity to the pivoted end thereof, with the blade in position disposed longitudinally of the members 10 and 11. The blade 40 extends such a distance from member 10 as to practically lightly touch or engage the opposite portion 42 of the member 11 with the members swung together, which thus forms a base for receiving a wire to be severed or cut. By the foregoing mounting and disposition of blade 40 adjacent the pivoted ends of members 10 and 11, the full effect of these members as long levers can be secured in a cutting operation, the wire being placed on the cutting base 42, and the members swung together to cause blade 40 to sever the wire.

20 The blade 40 can be detached and replaced by a sharp blade when found necessary.

A hook 50 is pivotally mounted transversely of and through the widened, grip forming portion of member 10, with the hook and bill thereof disposed transversely across and and freely swingable longitudinally of the outer side edge of member 10. With the staple puller disposed in position with the member 10 lowermost, as shown in Fig. 1, 30 the hook 50 depends downwardly therefrom in position to receive and hold the bail or handle of a bucket or other receptacle, and by locking the heads 20 and 30 together with clip 33, the handle 32 can be grasped and a receptacle secured to hook 50 readily transported, with the staple puller and hammer, as a unit, disposed horizontally and forming a holder and handle for the receptacle.

40 In operation and use of the staple pulling and hammer forming implement above described, when it is desired to pull or draw a staple, the clip 33 is swung to unlock heads 20 and 30, and arms 10 and 11. The staple engaging and drawing head 20 is then placed with the pointed end 22 thereof in position to engage and pass under the head of a staple, as clearly indicated by Fig. 1 of the accompanying drawings. By grasping the widened and concave-sided portion 25 of arm 10 with the fingers of one hand to hold head 20 in position, and grasping handle 32 of arm 11 in the other hand, arm 11 is raised and lowered to pound or strike hammer head 30 onto head 20 and drive or force the pointed end 22 thereof into the desired position under and engaging the staple head. After the end 22 of head 20 is driven or forced into staple engaging position, the arms 10 and 11 are forced upwardly with the curved outer surface 23 bearing on and against the member into which the staple is driven and forming a fulcrum surface therefor, so that the staple is easily and quickly pulled with a minimum of effort. The formation

and construction of the staple puller is such that a staple can be readily engaged and pulled thereby, irrespective of the position or condition thereof in and on a member in which driven.

70 When it is desired to employ the implement as a hammer, the spring locking clip 33 is swung over onto head 20 until stud 35 seats in depression 26 and locks heads 20 and 30, with arms 10 and 11, into position swung together to form a unitary structure having the hammer head formed by alined abutting heads 20 and 30, and the hammer handle formed by the parallel juxtaposed arms 10 and 11. Due to the formation of arms 10 and 11, in closed position locked together they together form a readily grasped handle at the outer or end away from the hammer head to provide the desired long lever or swinging action in using the hammer. In hammer forming position the inner side of the handle portion 32 of arm 11 is opposite the reduced or thin portion of arm 10, so that the hand fits readily around these opposite portions with 85 the fingers disposed under and through the handle 32.

90 The staple puller is of considerable utility in fence erection and repair work, as a bucket or similar handled receptacle can be supplied with staples and attached to hook 50 and readily transported with the implement as a handle to the point of operation. Then with the staple puller and hammer, together with the wire cutter 95 formed by blade 40, the necessary tools are always at hand for the desired work. The staple puller is preferably formed of a suitable metal and because of the simplicity of its construction will be durable 100 and withstand the usage to which put.

105 It is also evident that various changes, modifications, variations, and substitutions might be resorted to without departing from the spirit and scope of my invention, and hence I do not desire to limit myself to the exact and specific disclosures thereof.

110 Desiring to protect my invention in the broadest manner legally possible, what I claim and desire to secure by Letters Patent 115 of the United States, is:

120 1. In a staple puller, substantially parallel members pivoted together at one end for swinging movement toward and from each other, one of said members formed at its free end with a staple engaging head, and the other of said members formed at its free end with a hammer head for striking said engaging head when the members are swung together, and locking mechanism for detachably securing said members in position swung together with said heads alined to form a hammer head, said members providing a handle therefor.

125 2. In a staple puller, substantially parallel

- members pivoted together at one end for swinging movement toward and from each other, one of said members provided with a transversely disposed staple engaging head at its free end, and the other of said members provided with a transversely disposed hammer head at its free end for alinement with and striking said engaging head with the members swung together, 5
- 10 the staple engaging head member formed with a widened finger grasping portion adjacent said head, and the hammer head member formed with a handle portion adjacent the pivoted end thereof.
- 15 3. In a staple puller, substantially parallel members pivotally joined at one end, one of said members provided with a transversely disposed staple engaging head at its free end, and the other of said members provided with a transversely disposed hammer head at its free end for alinement with and striking said engaging head with the members swung together, said heads in alined engaged position spacing said members apart, a cutting blade disposed longitudinally of one of said members on the inner side adjacent the pivoted end thereof, and the inner side of the other member op- 20
- 25 posite said blade formed to provide a base for receiving a wire to be severed by said blade when the members are swung together. 30
4. In a staple puller, substantially parallel lever members pivotally connected together at adjacent ends for swinging movement toward and from each other, a transversely disposed staple engaging head on the free end of one of said members, said head extended outwardly from said members and curved inwardly toward and longitudinally thereof and pointed at its outer end, the outer longitudinal side of said head forming a curved fulcrum bearing surface, a transversely disposed hammer head at the free end of the other of said members positioned to strike and aline with the staple engaging head when the members are swung together, and a lock carried by one of said heads for detachably engaging the opposite head to secure the heads and members in position swung together to form a hammer head and handle therefor. 35 45 50

In testimony whereof I have hereunto set my hand at Kane, Pennsylvania, this 6th day of April, 1925.

JOHN AARON PETERSON.
